UNITED STATES PATENT OFFICE.

JAMES H. WALKER, OF MILWAUKEE, WISCONSIN, ASSIGNOR TO THE FULLER-WARREN CO., OF MILWAUKEE, WISCONSIN, A CORPORATION OF WISCONSIN.

GAS-RANGE.

1,161,427.

Specification of Letters Patent Patented Nov. 23, 1915.

Application filed May 8, 1912. Serial No. 695,818.

To all whom it may concern:

Be it known that I, JAMES H. WALKER, a citizen of the United States, residing at Milwaukee, in the county of Milwaukee and State of Wisconsin, have invented certain new and useful Improvements in Gas-Ranges, of which the following is a specification, reference being had to the accompanying drawing, forming a part thereof.

The main objects of the invention are to heat and utilize the whole or any part of the top of a gas range; to economize in the consumption of gas; to maintain a proper mixture of gas and air and hence proper combustion, without constant care or frequent regulation of burners; to avoid the inconvenience, uncleanliness and other objections incident to the use of open grids and the location of burners directly below the same; and generally to improve the construction and operation of gas cooking stoves or ranges.

It consists in the peculiar construction, arrangement and combination of parts as hereinafter particularly described and pointed out in the claims.

In the accompanying drawing like characters designate the same parts in the several figures.

Figure 1 is an end elevation as viewed from the left, of a gas range embodying the invention; Fig. 2 is a partial plan view of the same; Fig. 3 is a longitudinal section of the upper portion of one end of the range on the line 3-3, Figs. 1 and 2; and Figs. 4 and 5 are vertical cross sections of the upper part of the range on the lines 4-4, and 5-5, respectively, Figs. 2 and 3.

For the purpose of illustration, the invention is shown as embodied in a range divided centrally and transversely into two separate parts or sections, the upper portion of each part having a fire box or combustion chamber comprising four longitudinal heating flues for heating more or less of the top plate, but the invention may be embodied in a range or stove having more or less sections and heating flues according to the capacity required.

As the present invention relates more particularly to the provision for heating the top plate, and as both parts or sections of the range are alike, only the upper portion

of one part or section is shown in detail and will be specifically described.

55

As usual in the construction of gas ranges or stoves of this class, the space below the cooking top may be inclosed to form one or more ovens *a*. In the present case, the side and end walls *b* of the range and the top *c* wall *c* of the ovens are formed of sheet metal fastened to frame work of steel or iron.

At their upper edges the sheet metal side and end walls are bolted or riveted to the inner flange of a rectangular channel bar *d*, the flat or web side of the channel bar being placed uppermost. The sheet metal oven top *c* is supported upon angle bars *e*, riveted or bolted to the sheet metal end and side walls *b* of the range some distance below the frame *d*.

The top of the range on which cooking is done, as on the top of a coal or wood range, consists of a metal plate composed of separately removable sections *f* formed with longitudinal marginal flanges *g* on the under side, adapted to rest on angle bars *h* fastened to the front and back walls of the range just below the frame *d* and on the tops of longitudinal truss bars *i*. The truss bars *i* are of I-section or flanged on both sides at the top and bottom, and are removable supported at the ends by brackets *j* bolted or riveted to the end walls of the range and by a flanged cross bar *k* extending centrally across the range from front to rear and bolted or fastened at its ends to the front and rear angle bars *h*. The tops of the angle bars *h* and of the truss bars *i* are located in the same horizontal plane at a distance below the top of the frame *d* corresponding with the depth of the flanges *g* on the top plate sections, so that when the parts are assembled as shown in Figs. 3, 4 and 5, the upper plane faces of said sections will be flush with the top of the frame *d*.

The truss bars *i*, which are arranged parallel with and equidistant from one another and the front and rear walls of the range, divide the space between the top of the range and the top of the oven into a number of heating flues, in the present case four, at each end or in each of the two parts or divisions of the range. The sheet metal front and rear walls *b* and the sheet metal oven top *c* adjacent to the heating flues, are

protected by insulating sheets or boards *l* and *m*, of asbestos or other suitable material. The heating flues are provided at the bottom with a lining *o*, of fire brick or other refractory heat absorbing and reflecting material, removably supported between the truss bars *i* on the insulating sheet or board *m*. At the inner ends of the heating flues the range is provided on each side of 10 and parallel with the central cross bar *k*, which forms a partition between the two main parts or divisions of the fire box or combustion chamber, with an outlet flue *p*, which is closed at its front end and opens 15 at its rear end into a chimney pipe or connection *q*. Each flue *p* has a closed bottom and sides and is provided at the top, which is located some distance below the top flanges of the truss bars *i*, with a slide or 20 damper *r* for closing communication between it and the adjoining heating flues, except at its front or rear end. Each damper is provided at its front end with a handle *s* projecting through the front wall of the 25 range.

As shown in Fig. 3, the truss bars *i* are cut away at their inner ends below their top flanges above the flues *p* so as to afford communication between the adjoining heating flues at their inner ends and the transverse outlet flue in each part or division of the range. The webs of the truss bars *i* on each side of the central truss bar in each part or division of the range are preferably formed 35 with openings, as indicated by dotted lines in Fig. 3, to afford free communication between the adjoining heating flues, but the central bar is preferably made without such openings.

40. Some of the top plate sections *f* are preferably formed as shown in Figs. 2 and 3, with pot or kettle openings for quick work, especially in starting before the top has become hot, and these openings are provided 45 with griddles or lids *t* and reducing rings *u*. The several sections *f* of the top are also formed with apertures *v* to permit the escape of inert gas and the ingress of air to the flues when the range is connected with a 50 chimney, as it should be. Some of the sections are formed at the ends adjacent to the burners with air inlet and lighting openings *w*, as shown in Figs. 2 and 3, the edges of the sections next to these openings being 55 beveled, as shown in Fig. 3, so as to direct the flames issuing from the burners and the air entrained therewith, underneath the top plate.

The range is provided at each end with a 60 number of separately removable burners, comprising air and gas mixing tubes *x*, having flaring or enlarged air inlet openings at their lower ends and opening at their upper ends, which are bent laterally, into the heating flues in the direction of their length 65

and close to the top plate. These tubes are located entirely outside of the range, where they are unaffected by the heat, their upper laterally bent ends being inserted in openings in the end walls of the range and 70 formed or provided, as shown in Figs. 2 and 3, with lugs which engage with the outer ends of said end walls and hold the burners in place. They are removably secured in place by brackets *y*, fastened to the ends of the range, and clamping bars *z*, adjustably secured to the brackets by screws or other means. At their lower ends, which are 75 formed or provided with centrally perforated spiders or cross pieces, they are loosely 80 fitted and rest upon the ripples *2* of gas cocks *3* of a gas supply pipe *4* extending across the end of the range. Disks *5* for adjusting the supply of air admitted into the lower enlarged ends of the mixing tubes *x* 85 are threaded on the nipples *2*.

By the construction and arrangement of the burners above described, a Bunsen or hot blue flame is projected in a strong blast 90 through each heating flue from end to end thereof in contact with the top plate, the flame spreading laterally, and filling the channels between the longitudinal flanges of the top plate sections.

To facilitate the operation of the gas 95 cocks, rods *6* are pivotally connected at one end with crank arms *7* on the stems of the cocks and extend therefrom to the front of the range, where they are guided in a vertical plate or bar *8* attached to the range and 100 are formed or provided with knobs or handles *9*, as shown in Fig. 1. These knobs or handles are preferably grouped in a vertical series at each end of the range within clear 105 view and convenient reach of the operator, thereby not only facilitating the operation of the gas cocks but also indicating at a glance which of them are open and which closed.

In the present case the range, as shown 110 by the drawing, has two burners to each heating flue or section of the fire box or chamber, except the rear flue or section, which has but one, and the sections *f* of the top plate covering said flues are formed on the 115 under side with a middle rib or flange *10* parallel with the marginal flanges *g* and forming therewith channels for confining and directing the flames and heated products of combustion of the several burners. The 120 top sections *f*, covering the flue space above the dampers *r*, are preferably arranged lengthwise thereof and transversely to the other sections covering the heating flues or fire box sections, and do not have ribs or 125 flanges along the middle and the sides next to the heating flues, but are formed with end flanges, as shown in Figs. 3 and 5.

To admit an additional supply of air to the several heating flues or sections of the 130

fire box for producing and maintaining complete combustion of the fuel gas, openings *h* are formed in the walls *b* of the range below the discharge openings of the burner tubes *x*.

In the operation of the range, the gas cocks *g* of any desired number of burners, being opened according to the amount and kind of work to be done, by pulling the knobs or handles *h* which control such burners forward, the combustible mixture of gas and air as it issues from the discharge openings at the upper ends of the tubes *x*, is lighted through the openings *w* and produces sheets of flame, which are directed toward the outlet flue or flues *p* along the channels in the under side of the top sections *f*, which soon become heated sufficiently for the cooking operations to be performed thereon. Those portions of the top plate nearest the burners are naturally heated to and maintained at a higher temperature than those adjacent to the outlet flues, and the various articles to be cooked are arranged on the top plate accordingly, those requiring the greatest heat nearest the burners, and those requiring the least heat, nearest the outlet flues. For quick or immediate cooking, when the burners are first lighted and before the top plate has become thoroughly heated, the griddles or lids *t* are removed and pots or other cooking utensils are placed in the openings in direct contact with the burner flames.

At first, after lighting the burners, the dampers *r* are drawn forward so as to afford direct communication between the heating flues or fire box and the chimney pipe or connection *q* through the rear ends of the flues *p*, but after the walls of the flues have become heated sufficiently to maintain the proper draft, the dampers are pushed back, closing the inlets to the flues *p* at their rear ends and opening them at their front ends. The waste or flue gases then passing indirectly through the outlet flues *p*, the entire width of the range to the chimney connection, impart heat to the walls of said flues and to adjacent sections of the top plate, the temperature of such gases being thereby lowered before they enter the chimney and heat being correspondingly saved and utilized.

When the burners have been in operation for some time, the fire brick forming the bottom walls of the heating flues become highly heated, reflecting their heat to the top plate and aiding combustion of the fuel gas passing over them. The highly heated fire brick also serve to vaporize, consume or destroy any liquid or solid foods spilled or dropped through the openings in the top plate, the resulting vapors, smoke and any offensive fumes or odors being conducted off through the outlet flues *p* into the chimney.

Thus the consumption or destruction of liquids or solids spilled or falling upon the range and into the heating flues or fire box, keep the range in a cleanly and sanitary condition without care or attention. After the walls of the heating flues or fire box have become highly heated, the gas supply to alternate burners or to some of the burners may be shut off, and the required degree of heat for such cooking operations as are in progress may be maintained by the operation of the remaining burners. When a small or limited amount of cooking is to be done, only that portion of the top plate which is required, needs to be heated, the burners supplying other portions of the top remaining out of use, thus economizing in the consumption of fuel.

The location of the burners entirely outside of the range, where they are not subjected to great variations of temperature, avoids variations in the supply of air thereto and in the resulting mixture of air and gas, thereby maintaining the proper quality of the burner flame for the production of the greatest amount of heat for a given consumption of gas, whatever length of time the burners may be in use. This location of the burners also prevents carbonization and reduced efficiency thereof resulting from variation in the temperature and overheating of the mixture before ignition takes place, and avoids the necessity of constant attention and frequent adjustment and regulation of the gas and air supply to the several burners.

By the construction herein shown and described, the top plate sections *f*, truss bars *i*, outlet flues *p* with the dampers *r*, fire brick *o* and insulating linings *l* and *m*, being removable, afford ready access to the several parts for inspection or repair, and facilitate replacing them.

Various changes in the details of construction and arrangement of parts of the range may be made without departing from the spirit and scope of the invention.

I claim:

1. In a gas range the combination of a top plate forming the top wall of a horizontal flue having an outlet opening or connection at one end and an ascending burner tube opening laterally at its upper end into the opposite end of said flue in the direction of its length and toward said outlet opening or connection and having a gas supply connection and air inlet at its lower end.

2. In a gas range the combination with a top plate forming the top wall of a horizontal flue having an outlet connection or opening at one end and an air inlet at the opposite end, and an ascending burner tube opening laterally at its upper end into the air inlet end of said flue in the direction of

- its length toward said outlet connection or opening and close to said top plate and having a gas supply connection and air inlet at its lower end.
- 5 3. In a gas range the combination with a top cooking plate forming the top wall of a horizontal flue, having an outlet connection or opening at one end, and an ascending burner tube opening laterally at its upper 10 end into the opposite end of said flue in the direction of its length and toward said outlet connection or opening and having a gas supply connection and an air inlet at its lower end, the top plate having an air inlet 15 and lighting opening adjacent to the discharge orifice of the burner tube.
4. In a gas range the combination with a top plate forming the top wall of a number of parallel horizontal heating flues, an outlet flue arranged transversely to said heating flues at one end thereof, means for opening and closing communication between said heating flues and either end of the outlet flue, and burner tubes opening into the opposite 20 ends of said heating flues in the direction of their length.
5. In a gas range the combination with a top plate forming the top wall of a number of parallel horizontal heating flues communicating with one another at their outlet ends, an outlet flue arranged transversely to said heating flues at their outlet ends and some distance below the top plate, and provided with a damper for alternately opening 25 and closing communication between the ends of said outlet flue and the heating flues, and burner tubes opening into the opposite ends of the heating flues in the direction of their length.
- 40 6. In a gas range the combination of a cooking plate forming the top wall of a number of parallel horizontal flues having an outlet at one end, and ascending burner tubes having at their upper ends lateral 45 openings directed into the several flues lengthwise thereof at the ends opposite and toward said outlet and having at their lower ends air inlets and independently controlled gas supply connections.
- 50 7. In a gas range the combination of a top frame, flanged truss bars removably supported at the ends in said frame some distance below the top of the same and dividing the space below the top of the range into 55 heating flues, an outlet flue communicating with the heating flues at one end thereof, a top plate composed of removable sections formed on the under side with longitudinal flanges adapted to rest on said bars and to 60 form channels for the burner flames, and burner tubes opening into said heating flues in the direction of the length thereof and at the ends opposite said outlet flue.
8. In a gas range the combination of top 65 frame work, truss bars supported at the ends in said frame work some distance below the top of the range, a top plate composed of removable sections adapted to rest on said bars, a horizontal layer of refractory material arranged below the top 70 plate and forming therewith a heating flue space, an outlet connection with said space adjacent to one end of the bars, and burner tubes opening into said space adjacent to the opposite ends of the bars and in the direction of the length thereof.
9. In a gas range the combination of top frame work, flanged truss bars removably supported at the ends in said frame work some distance below the top of the range, 80 a top plate composed of removable sections formed on the under side with longitudinal flanges adapted to rest on said bars and frame work, a layer of refractory material composed of removable sections fitted between said bars and forming with the top plate a heating flue space, an outlet connection communicating with said space adjacent to one end of said bars, and burner tubes opening into said space adjacent to 85 the opposite ends of said bars and in the direction of their length.
10. In a gas range the combination with top frame work and inclosing side and end walls, of a top plate composed of removable 90 sections having longitudinal flanges on the under side thereof adapted to rest on said frame work and forming therewith flame confining and directing flues, an outlet connection with which said flues communicate 95 at one end, and ascending burner tubes opening at their upper ends into the opposite ends of said flues in the direction of their length and close to the top plate and having at their lower ends gas supply connections 100 and air inlets.
11. In a gas range the combination with a top cooking plate, of a parallel wall or partition forming therewith a horizontal flue space, an outlet connection communicating with said space at one end thereof, and burners located outside of the range and comprising ascending mixing tubes having 110 gas and air supply connections at their lower ends, extending upwardly therefrom and opening laterally at their upper ends into said flue space close to the top plate at the end opposite and toward the outlet connection.
12. In a gas range the combination of a metal plate and a parallel heat absorbing and reflecting wall forming the upper and lower walls respectively of a horizontal flue and combustion chamber having an outlet 120 at one end and an ascending burner tube opening laterally at its upper end into the opposite end of said flue in the direction of its length and toward said outlet and having at its lower end a gas supply connection and air intake.

13. In a gas range the combination of a number of upright burners located adjacent to one end of the range and having gas supply connections provided with cocks and operating rods of different lengths connected with said cocks and provided with handles arranged one above another at the front and adjacent to one end of the range.

14. In a gas range the combination of a number of upright burners located adjacent to one end of the range and provided with cocks having crank arms arranged in a

transverse series across the end of the range, operating handles arranged in a vertical series at the front of the range, and obliquely arranged rods of different lengths connecting the handles with said crank arms. 15

In witness whereof I hereunto affix my signature in presence of two witnesses.
